UNITED STATES PATENT OFFICE.

GUGLIELMO MARCONI, OF LONDON, ENGLAND, ASSIGNOR TO MARCONI WIRELESS TELEGRAPH COMPANY OF AMERICA, OF NEW YORK, N. Y., A CORPORATION OF NEW JERSEY.

DUPLEX WIRELESS TELEGRAPHY.

1,116,309.

Specification of Letters Patent.

Patented Nov. 3, 1914.

Application filed May 1, 1912. Serial No. 694,347.

To all whom it may concern:

Be it known that I, GUGLIELMO MARCONI, a subject of the King of Italy, residing in London, England, have invented certain new and useful Improvements in Duplex Wireless Telegraphy, of which the following is a specification.

The object of this invention is to provide a duplex system of wireless telegraphy such that messages may be sent to and received from a distant station simultaneously without interference. In such a system it is necessary to have separate transmitting and receiving apparatus at any one station; and when messages are to be sent over great distances it is necessary to produce vibrations of great magnitude. But the proximity of the transmitting apparatus to the receiving apparatus in any one station results in the transmission of vibrations of such magnitude from the transmitting apparatus to the receiving apparatus in the same station, that it is difficult, if not impossible, to cause the receiving apparatus to respond to the signals of the distant station.

One of the principal objects of this invention, therefore, is to provide means for counteracting the effect of the transmitting apparatus upon the receiving apparatus in the same station so as to eliminate the disturbing effect of the transmitting apparatus upon the receiving apparatus at that station, and to enable this receiving apparatus to be responsive to the relatively weak signals sent from a distant station. I obtain these results by combining the aerials at the receiving station in a certain manner, by locating the aerials at the stations in certain relative positions to each other and by connecting the apparatus in a manner which will be more fully hereinafter explained.

In my Letters Patent No. 924,168, issued June 8, 1909, I showed that Hertzian waves could be directed by locating the aerials in certain positions relatively to each other, and I there showed that the maximum effect in a given direction could be obtained by using an aerial substantially horizontal to the surface of the earth and pointing away from the direction in which the signals were to be directed. By pointing away, I mean that the end of the aerial which is earthed or grounded, is placed nearest the distant

station to which it was desired to send the messages, and that the unearthing or free end of the aerial is placed farthest from the distant station. In these Letters Patent I also showed that the maximum effect was obtained at a receiving station by locating the aerial at that station horizontally in the same vertical plane as, and pointing away from, the sending aerial. In this position the grounded or earthed end of the receiving aerial is placed nearest the distant transmitting station and the free or unearthing end farthest from it. In Figure 3 of said Letters Patent I showed an arrangement consisting of a plurality of horizontal aerials radiating in different directions, but only one of which could be used at any one time, as a sending or receiving aerial, depending upon the position of the distant station to which it was desired to send or from which it was desired to receive.

In the drawings accompanying this specification I have shown in Fig. 1 a diagram illustrating the relative positions of the aerials in two stations arranged according to my present invention. In Fig. 2 I have shown more in detail the apparatus of one of the stations, it being, however, shown diagrammatically for the purpose of illustrating apparatus which is operative, it being obvious that almost any standard transmitting or receiving apparatus may be used in connection with the aerials shown and that many of the connections may be varied without affecting the operation of the system.

Referring to Fig. 1, I have shown at T A₁, the transmitting aerial of a station, say station No. 1, which is preferably located horizontally and is grounded at one end. At R A₁ I have shown the receiving aerial at the same station which is also preferably horizontal and parallel to T A₁ and is located a short distance from T A₁ and preferably at the side of T A₁ and thus receives the minimum effect from it. At B A₁ I have shown a third aerial which I will term the balancing aerial. This aerial is grounded at one end and is preferably horizontal and arranged to point away from the plane of the transmitting aerial T A₁. In this position it receives the maximum or nearly the maximum effect from aerial T A₁. These

three aerials T A₁, R A₁ and B A₁, constitute the three aerials of one station. The receiving and balancing aerials are located in the same place, and combined with each other, but are removed a short distance from the transmitting aerial. This distance may be a fraction of the distance of the station from the distant station with which it is to communicate. I have found that good results are obtained by separating these aerials a distance equal to 0.4 per cent. of the distance between the distant stations. If the transmitted and received oscillations be of different wave lengths the distance between the transmitting and receiving apparatus may be reduced; the effect of the waves from the transmitting aerial T A₁ is then to impulse these two aerials and to set them both oscillating with their own natural frequency which, however, is not that of these waves. At R A₂ I have shown the receiving aerial at a distant station, say station No. 2, with which the station first described (No. 1) is to communicate. This aerial is arranged to point away from the transmitting aerial T A₁ and is preferably arranged horizontally and in the same vertical plane as T A₁, as shown in my Letters Patent No. 924,168, and thus obtains the maximum effect of the transmitting aerial T A₁. It is, of course, unnecessary that the receiving aerial be in exactly the same plane as the transmitting aerial, substantial coincidence of plane being sufficient. Located at the same place as and combined with aerial R A₂ is a balancing aerial B A₂, preferably arranged horizontally and pointing away from T A₂. It is preferably also at right angles to the transmitting aerial T A₁ and consequently is only very slightly, if at all, affected by the signals sent from aerial T A₁. Located a short distance from the receiving and balancing aerials R A₂ and B A₂ is their transmitting aerial T A₂, which is designed to transmit to the receiving aerial R A₁ of the distant station. T A₂ is preferably placed horizontally in the same vertical plane as, and pointing away from, receiving aerial R A₁. The relative positions of the aerials are preferably as follows: Transmitting aerial T A₁ is parallel to receiving aerial R A₁, at right angles to balancing aerial B A₁, and in the same plane as and pointing away from receiving aerial R A₂, to which it transmits, so as to transmit to it with maximum effect. Receiving aerial R A₂ is in the same plane as, and points away from, transmitting aerial T A₁, so as to obtain the maximum effect from that aerial, but is parallel to its own transmitting aerial T A₂, so as to receive with minimum effect from it. Balancing aerial B A₂ is at right angles to transmitting aerial T A₁, so as to receive with minimum effect from it, and points away from its own transmitting aerial T A₂,

in order to receive therefrom the maximum effect. The fact that balancing aerial B A₂, and transmitting aerial T A₂ and balancing aerial B A₁, and transmitting aerial T A₁, are not located in the same planes has little effect as to the transmitting and balancing aerials of each station are in such close proximity. The relative locations of transmitting aerial T A₂ and balancing aerial B A₁ and receiving aerial R A₁ are preferably the same as those described above, the transmitting aerial T A₂ being in the same plane as and pointing away from receiving aerial R A₁, and the balancing and receiving aerials B A₁ and R A₁ being preferably perpendicular to each other. It is preferable to locate the balancing aerial at a less height than the receiving aerial at the same station, as it will therefore be affected to a less degree by the transmitting apparatus at the distant station.

Fig. 2 shows the general arrangement of one of the stations, say station No. 1, the arrow indicating the direction of station No. 2 to which it is desired to transmit and from which it is desired to receive. Aerial T A₁ contains the primary, a transformer 1, so that an inductive coupling may be made with an oscillation circuit containing the secondary, 2, a producer of electrical oscillations of high frequency, indicated at 3, variable condenser 4, source of power 5, and sending key 6. I prefer to inductively couple the oscillation circuit to the aerial, although any other method of coupling may be used, and the oscillation circuit may take any form. The receiving apparatus at this station preferably consists of the following apparatus, although any suitable receiving apparatus may be used instead, the drawing being merely diagrammatic of the form I preferably employ. The receiving aerial R A₁ has in it the primary of a transformer 7, and the balancing aerial B A₁ has in it the primary of a transformer 8, the primaries of both being adjustable. It will be noted that the circuits of these aerials are so arranged that the effect of the oscillations in one aerial is opposed by the effect in the other aerial. Surrounding the primaries 7 and 8 is the secondary of a transformer 9 which is included in the receiving circuit, which circuit preferably contains a variable condenser 10, and a detector 11 which actuates a telephone or other suitable instrument 12. Inasmuch as the transmitting and receiving apparatus at the same station may be separated several miles from each other, and inasmuch as I preferably locate the operators at the receiving apparatus of the station, I provide means for actuating and controlling the transmitting apparatus from the location of the receiving apparatus. This means I have shown in the form of a telegraph line consisting of wires 13 ex-

tending between the location of the receiving and transmitting ends, a battery 14, and a key 15 adapted to close the circuit and energize an electro-magnet 16 thus actuating key 6.

The operation of my invention is as follows: Assuming that both stations 1 and 2 are sending and receiving simultaneously, transmitting aerial T A₁ will be sending out signals to the distant station (No. 2), the maximum signals being in the direction of the arrow. Owing to the proximity of the receiving and balancing aerials R A₁ and B A₁, they will also receive the signals emanating from the transmitting aerial T A₁. Balancing aerial B A₁, however, being pointed away from the transmitting aerial T A₁, will receive the maximum, or very nearly the maximum signal, while receiving aerial R A₁ being pointed away from transmitting aerial T A₂, will receive the maximum signal received at station No. 1 from that transmitting aerial, as well as strong signals from the transmitting aerial T A₁, owing to its proximity. The effect produced in balancing aerial B A₁ by the transmitting aerial T A₁ is, however, opposite to that produced by the transmitting aerial T A₁ in the receiving aerial R A₁, and thus if the inductance, capacity, resistance and coupling of balancing aerial B A₁ be properly adjusted, and if the periodicity of balancing aerial B A₁ and receiving aerial R A₁ are the same, the effect of the transmitting aerial upon the balancing and receiving aerials can be made equal and opposite, and thus counterbalance each other, so that no effect is obtained in the receiving circuit from the local transmitting aerial. This allows the receiving apparatus to receive the signals from the distant transmitting aerial T A₂ without any interference from transmitting aerial T A₁. In order that the effects in the balancing and receiving aerials be equal and opposite, it is preferable that the phase relation of the oscillations in the two aerials be the same. The relation of these phases depends on the relation of the respective distances of the balancing and receiving aerials from the transmitting aerial at any one station, and these distances may be altered by moving balancing aerial B A₁ nearer to or farther from, transmitting aerial T A₁. Where, however, this is impossible, the phase relation may be altered by combining the effect of two or more balancing aerials, or by any other well-known method of phase shifting. The operation of station No. 2 is the same as station No. 1 and it will thus be seen that in each station the disturbing effect of the local transmitting apparatus is neutralized, thus permitting the receiving apparatus to receive the signals of the distant station.

It is not necessary for the practice of my invention that all of the aerials be directive, as it is possible to obtain similar results using one vertical aerial and one directive, the balancing aerial, however, being preferably horizontal. In general, better results are secured when all of the aerials are directive as described.

I do not intend to limit myself to the precise details shown and described as it is obvious that they may be varied within wide limits without departing from the spirit of my invention. For instance, more than one aerial may be used in each location, and wherever I have used the term aerial in this specification, I have intended to include a plurality of aerials co-operating to produce the same result. Other modifications that may be made are, for instance, changes in the receiving and transmitting circuits, for different connections may be used therein to produce the same results, a large number of different arrangements being known to the art, or other apparatus may be used in several of the locations, a large number of different detectors, etc., being now used, or the coupling may be varied, instead of being as shown in Fig. 2, the coils of the transformer may be arranged concentrically or an electrostatic or other form of coupling may be used.

While I have shown the receiving, transmitting and balancing aerials as being grounded or earthed as at E, yet it is not essential to the practice of my invention that any of them be grounded for they may be connected to capacities or the transmitting and receiving aerials may be connected to capacities or the earth and the balancing aerial prolonged in the direction of the local transmitting aerial without being grounded.

What I claim and desire to secure by Letters Patent is:

1. In a station for wireless telegraphy, the combination of transmitting apparatus, receiving apparatus comprising two aerials disposed at an angle to each other and means for opposing the effect produced by the transmitting apparatus in one aerial by the effect produced by the transmitting apparatus in the other aerial.

2. In a station for wireless telegraphy, the combination of transmitting apparatus, receiving apparatus comprising a receiving aerial and a balancing aerial at least one of said aerials being directive and means for opposing the effect produced by the transmitting apparatus in the receiving aerial by the effect produced by the transmitting apparatus in the balancing aerial.

3. In a station for wireless telegraphy, the combination of transmitting apparatus, receiving apparatus comprising two aerials removed a short but not each an equal distance from the transmitting apparatus and

- means for opposing the effect produced by the transmitting apparatus in one aerial by the effect produced by the transmitting apparatus in the other aerial.
4. In a station for wireless telegraphy, the combination of transmitting apparatus, receiving apparatus comprising two aerials pointed at an angle to one another and means for opposing the effect produced by the transmitting apparatus in one aerial by the effect produced by the transmitting apparatus in the other aerial.
5. In a station for wireless telegraphy, the combination of transmitting apparatus, receiving apparatus removed a short distance from the transmitting apparatus and comprising a receiving aerial and a balancing aerial pointed at an angle to one another, and means for opposing the effect produced by the transmitting apparatus in the receiving aerial by the effect produced by the transmitting apparatus in the balancing aerial.
6. In a station for wireless telegraphy, the combination of transmitting apparatus, receiving apparatus removed a short distance from the transmitting apparatus, and comprising a receiving aerial and a balancing aerial tuned to the same periodicity at least one of said aerials being directive, and means for opposing the effect produced by the transmitting apparatus in one aerial by the effect produced by the transmitting apparatus in the other aerial.
7. In a station for wireless telegraphy, the combination of transmitting apparatus, receiving apparatus comprising a receiving aerial and a balancing aerial pointed at an angle to one another and tuned to the same periodicity, and means for opposing the effect produced by the transmitting apparatus in the receiving aerial by the effect produced by the transmitting apparatus in the balancing aerial.
8. In a station for wireless telegraphy, the combination of transmitting apparatus, receiving apparatus removed a short distance from the transmitting apparatus and comprising a receiving aerial and a balancing aerial pointed at an angle to one another and tuned to the same periodicity, and means for opposing the effect produced by the transmitting apparatus in the receiving aerial by the effect produced by the transmitting apparatus in the balancing aerial.
9. In a station for wireless telegraphy, receiving apparatus comprising two horizontal aerials pointed at an angle to one another and a receiving circuit coupled to both.
10. In a station for wireless telegraphy, receiving apparatus comprising a receiving aerial, a balancing aerial and a receiving circuit coupled to both receiving aerial and balancing aerial at least one of said aerials being directive.
11. In a station for wireless telegraphy, receiving apparatus comprising a receiving aerial, a balancing aerial pointed at an angle to the receiving aerial, and a receiving circuit coupled to both receiving and balancing aerials.
12. In a station for wireless telegraphy, transmitting apparatus comprising an aerial, receiving apparatus comprising a receiving aerial, a balancing aerial and a receiving circuit coupled to both receiving and balancing aerials at least one of said aerials in the receiving apparatus being directive.
13. In a station for wireless telegraphy, transmitting apparatus comprising an aerial, receiving apparatus comprising a receiving aerial, a balancing aerial and a receiving circuit coupled to both receiving and balancing aerials and means for opposing the effect produced by the transmitting apparatus in the receiving aerial by the effect produced by the transmitting apparatus in the balancing aerial at least one of said aerials in the receiving apparatus being directive.
14. In a station for wireless telegraphy, transmitting apparatus comprising an aerial, receiving apparatus removed a short distance from the transmitting apparatus and comprising a receiving aerial, a balancing aerial pointed at an angle to the receiving aerial and a receiving circuit coupled to both receiving and balancing aerials, and means for opposing the effect produced by the transmitting apparatus in the receiving aerial by the effect produced by the transmitting apparatus in the balancing aerial.
15. In a station for wireless telegraphy, the combination of transmitting apparatus comprising an aerial, receiving apparatus comprising a receiving aerial, and a balancing aerial tuned to the same periodicity, the receiving and balancing aerials being pointed at an angle to one another, a receiving circuit coupled to both receiving and balancing aerials, and means for opposing the effect produced by the transmitting apparatus in the receiving aerial by the effect produced by the transmitting apparatus in the balancing aerial.
16. In a station for wireless telegraphy, a receiving aerial containing the primary of a transformer, a balancing aerial containing the primary of a transformer, and a receiving circuit containing the secondary of a transformer inductively related to the two primaries at least one of said aerials being directive.
17. In a station for wireless telegraphy, a receiving aerial containing the primary of a transformer, a balancing aerial pointed at an angle to the receiving aerial and containing the primary of a transformer and a receiving circuit containing the secondary of a transformer surrounding the two primaries and inductively related thereto.

18. In a station for wireless telegraphy, the combination of transmitting apparatus, receiving apparatus comprising two aerials, one of which is directional, and means for opposing the effect produced by the transmitting apparatus in one aerial by the effect produced by the transmitting apparatus in the other aerial.
19. In a station for wireless telegraphy, the combination of a transmitting aerial, receiving apparatus comprising two aerials one a receiving aerial and the other a balancing aerial, the receiving aerial being located substantially parallel with the transmitting aerial, and the balancing aerial being located at an angle to the transmitting aerial.
20. In a station for wireless telegraphy, the combination of a transmitting aerial, receiving apparatus comprising two aerials, one a receiving aerial and the other a balancing aerial, the receiving aerial being located substantially parallel with the transmitting aerial, and the balancing aerial being located at an angle to the transmitting aerial and pointing away from the transmitting aerial.
21. In a station for wireless telegraphy, transmitting apparatus comprising an aerial, receiving apparatus removed a short distance from the transmitting apparatus and comprising a receiving aerial pointed parallel to the transmitting aerial, a balancing aerial pointed at an angle to the transmitting aerial, a receiving circuit coupled to both receiving and balancing aerials, means for opposing the effect produced by the transmitting apparatus in the receiving aerial by the effect produced by the transmitting apparatus in the balancing aerial, and means for controlling the transmitting apparatus from the location of the receiving apparatus.
22. In a station for wireless telegraphy, the combination of transmitting apparatus comprising an aerial, receiving apparatus removed a short distance from the transmitting apparatus and comprising a receiving aerial pointed parallel to the transmitting aerial, a balancing aerial pointed at an angle to the transmitting aerial, both receiving and balancing aerials being tuned to the same periodicity, a receiving circuit coupled to both receiving and balancing aerials, means for opposing the effect produced by the transmitting apparatus in the receiving aerial by the effect produced by the transmitting apparatus in the balancing aerial and means for controlling the transmitting apparatus from the location of the receiving apparatus.
23. In a system of duplex wireless telegraphy, a plurality of stations each containing a transmitting aerial, a receiving aerial and a balancing aerial at least one of said aerials being directive.
24. In a system of duplex wireless telegraphy, a plurality of stations each containing a transmitting aerial, a receiving aerial and a balancing aerial at least one of said aerials being directive, the receiving and balancing aerials of the several stations being respectively parallel.
25. In a system of duplex wireless telegraphy, a plurality of stations each containing a transmitting aerial, and a balancing aerial, the transmitting aerials of each station being at an angle to the balancing aerials of the others.
26. In a system of duplex wireless telegraphy, a plurality of stations each containing a transmitting aerial and a balancing aerial, the balancing aerial of each station pointing away from the transmitting aerial in that station and being at an angle to the transmitting aerials of the other stations.
27. In a system of duplex wireless telegraphy, a plurality of stations each containing a transmitting aerial and a receiving aerial, the receiving aerial of each station being in a plane parallel to the plane of the transmitting aerial in that station, and in the same plane as the plane of the transmitting aerials of the other stations.
28. In a system of duplex wireless telegraphy, a plurality of stations each containing a transmitting aerial, a receiving aerial and a balancing aerial, the balancing aerial of each station being at an angle to the planes of the transmitting and receiving aerials of that station and the transmitting aerials of the other stations.
29. In a system of duplex wireless telegraphy, a plurality of stations each having a transmitting aerial, a receiving aerial, and a balancing aerial, the transmitting aerial of one station and the balancing and receiving aerials of the distant stations with which it is desired to communicate being tuned to the same periodicity.
30. In a system of duplex wireless telegraphy, a plurality of stations each comprising horizontal transmitting, receiving and balancing aerials.
31. In a system of duplex wireless telegraphy, a plurality of stations each comprising a transmitting aerial and horizontal receiving and balancing aerials.
32. In a system of duplex wireless telegraphy, a plurality of stations each comprising a receiving aerial and horizontal transmitting and balancing aerials.
33. In a system of duplex wireless telegraphy, a plurality of stations each comprising a transmitting aerial, a receiving aerial and a horizontal balancing aerial.
34. In a system of duplex wireless telegraphy, a station comprising a transmitting aerial, a receiving aerial, and a balancing aerial horizontally disposed and pointing away from the transmitting aerial.

35. In a system of duplex wireless telegraphy, a station comprising a transmitting aerial, a receiving aerial and a balancing aerial, the balancing aerial being horizontally disposed and pointing away from the transmitting aerial, and the receiving aerial being horizontally disposed and parallel to the transmitting aerial.

36. In a system of duplex wireless telegraphy, two stations each containing a transmitting aerial, a receiving aerial and a balancing aerial, the balancing and receiving aerials of one station being horizontally disposed and respectively at an angle to and in the same plane as the transmitting aerial of the other station.

37. In a system of duplex wireless telegraphy, two stations each comprising a transmitting aerial, a receiving aerial and a balancing aerial, the receiving aerial of each station being horizontally disposed and in the same plane as and pointing away from the transmitting aerial of the other station, the balancing aerial of each station being horizontally disposed at an angle to the transmitting aerial of the other station and pointing away from the transmitting aerial of its own station.

38. In a station for wireless telegraphy, the combination of a transmitting aerial, receiving apparatus comprising two aerials, one a receiving aerial and the other a balancing aerial, the balancing and receiving aerials being located at substantially right angles to one another.

39. In a station for wireless telegraphy, the combination of a transmitting aerial, receiving apparatus comprising two aerials one a receiving aerial and the other a balancing aerial, the receiving aerial being located substantially parallel with the transmitting aerial and the balancing aerial being located at substantially right angles to the transmitting aerial.

40. A system of duplex wireless telegraphy, comprising a plurality of stations

each containing a transmitting aerial a balancing aerial and a receiving aerial, the balancing and receiving aerials at each station being located at an angle to one another, but the receiving aerial at one station being located substantially parallel with the transmitting aerial at the other distant station.

41. A system of duplex wireless telegraphy, comprising a plurality of stations each containing a transmitting aerial a balancing aerial and a receiving aerial, the balancing and receiving aerials at each station being located at an angle to one another but the balancing aerial being located at an angle to the transmitting aerial at the other distant station.

42. A system of duplex wireless telegraphy, comprising a plurality of stations, each station containing a transmitting aerial, a balancing aerial and a receiving aerial, the transmitting aerials at each station being located in substantially the same plane, the receiving aerials at the two stations being located in substantially the same plane and the balancing aerials at each station being located at an angle to the transmitting and receiving aerials at that station.

43. A system of duplex wireless telegraphy, comprising a plurality of stations, each station containing a transmitting aerial, a balancing aerial and a receiving aerial, the transmitting aerials at the two stations being located in substantially the same plane with one another, but pointing away from one another, the receiving aerials being located in substantially the same plane but pointing away from one another, and each balancing aerial being located at an angle to the transmitting aerial at its own station.

In witness whereof I have hereunto signed my name in the presence of two witnesses.

GUGLIELMO MARCONI.
